COMBINED PAPER TOWEL AND TISSUE DISPENSER

Henry R. Johannes, Allentown, Pa., assignor to Caloric Corporation, Topton, Pa., a corporation of Pennsylvania

Filed Feb. 11, 1964, Ser. No. 78,589

Term of patent 14 years

(Cl. D52—2)

Fig. 1.

Fig. 2.

Fig. 3.

FIG. 1 is a front elevational view of a combined paper towel and tissue dispenser embodying the new design.

FIGS. 2 and 3 are opposite perspective views of the same.

The facial tissue and roll of hand towels shown in broken lines are depicted for illustrative purposes only.

I claim:

The ornamental design for a combined paper towel and tissue dispenser, as shown and described.
